UNITED STATES PATENT OFFICE.

FRED A. CULVER, OF WORCESTER, MASSACHUSETTS, ASSIGNOR TO CULVER STEARNS MANUFACTURING COMPANY, OF WORCESTER, MASSACHUSETTS, A CORPORATION OF MASSACHUSETTS.

DESIGN FOR A COMBINATION SIGNAL AND TAIL LAMP.

Application filed January 13, 1923. Serial No. 4,878. Term of patent 7 years.

To all whom it may concern:

Be it known that I, FRED A. CULVER, a citizen of the United States, residing at Worcester, in the county of Worcester and State of Massachusetts, have invented a new, original, and ornamental Design for a Combination Signal and Tail Lamp, of which the following is a specification, reference being had to the accompanying drawing, forming part thereof.

Fig. 1 is a rear elevation;

Fig. 2 is a side view showing my new design.

I claim:

The ornamental design for a combination signal and tail lamp, as shown.

FRED A. CULVER.
